United States Patent Office

Des. 188,281
Patented June 28, 1960

188,281

TOY CLOCK

Bayard C. Reed, Chicago, Ill., assignor to
Marvin I. Glass, Chicago, Ill.

Filed Aug. 31, 1959, Ser. No. 57,387

Term of patent 14 years

(Cl. D34—15)

Fig. 1

Fig. 2

Fig. 3

Fig. 4

Figure 1 is a perspective view of a toy clock showing my new design;

Figure 2 is a front view;

Figure 3 is a rear view; and

Figure 4 is a side view thereof.

I claim:

The ornamental design for a toy clock, substantially as shown.
